UNITED STATES PATENT OFFICE.

JULIUS BECKER, OF SYRACUSE, NEW YORK, ASSIGNOR TO SEMET-SOLVAY COMPANY, OF SOLVAY, NEW YORK, A CORPORATION OF NEW YORK.

APPARATUS FOR REMOVING OVEN DOORS.

Application filed December 8, 1921. Serial No. 521,064.

To all whom it may concern:

Be it known that I, JULIUS BECKER, a citizen of the United States, residing at Syracuse, in the county of Onondaga and 5 State of New York, have invented a new and Improved Apparatus for Removing Oven Doors, of which the following is a specification.

My invention relates particularly to 10 means for removing and setting in place the doors of retort coke ovens and the object of my improvements is to provide efficient and convenient means for this purpose which shall be operable with the expenditure of a minimum of power and in 15 such a manner that the removal and resetting of the door shall be effected without loosening or otherwise injuring the door frame.

20 The invention will be best understood by reference to the accompanying drawings, illustrating an embodiment thereof, Fig. 1 of which shows a side view of the device, Fig. 2, shows a side view on an enlarged 25 scale of the door engaging and lifting mechanism in position to begin the disengaging of the door from its socket, Fig. 3 shows the lifting mechanism withdrawn from the door, Fig. 4 shows a plan view of 30 the device, Fig. 5 shows a front elevation of the same, Fig. 6 shows a vertical section on the line 6—6, Fig. 4, Fig. 7 is an enlarged 35 view partly in section of the unlatching rod and gears and Fig. 8 is a side view of a modified form of the device.

Referring to the drawings, 1, indicates 40 a carriage, mounted upon wheels, 2, 2, which are adapted to run on track, 3, 3, along in front of a battery of ovens so that the apparatus may be shifted from place to place as required along the face of the battery so as to engage the several doors.

Upon the carriage, 1, is mounted a ram, 4, carried on wheels 5, 5, 5, which is inclined slightly downward toward the ovens and is provided with a head, 4^a, to which is secured the door engaging mechanism. The ram, 4, is arranged to be moved toward or from the oven doors by means of a motor 45 6, gear train, 7, and pinion, 8, which engages with a rack, 9, carried on the ram, 4. The rack, 9, is held in place by guides, 10, 10, and is movably independently of the movement of the ram, 4, but in the same direction, within limits fixed by the engagement

of stops, 11, 11^a, with lugs, 12, 12^a. Between the stops 11, 11^a, is located shock absorbing spring, 13. Connected at one end to rack, 9, by push rod, 14, and link, 15, is thrust lever, 16, which is pivotally mounted on 60 ram, 4, by pin, 17, and is connected at the other end by pin, 18, to thrust arms, 19, 19. These thrust arms, 19, are suspended by links 20, 20, from pin 21 and carry thrust rollers, 22, 22, which bear upon the door frame when the lifting mechanism is in position for operation. Thrust lever 16, is further connected to ram, 4, by spring 23, which is so arranged as to normally hold the thrust arms, 19, extended to the limit of 70 their forward movement.

The door engaging mechanism consists of a door engaging hook 24, at the end of hook arm 24^a and having curved cheeks, 25, which is adapted to engage a recess, 26, in door, D. The hook arm, 24^a, is mounted on supporting pin, 21, and may be adjusted to various heights of doors, and to engage the door socket, 26, by means of screw, 27, and nut 28, which is connected to pin, 48, 80 which passes through the inner end of arm, 24^a. The screw, 27, is revolved by gears, 29, and hand wheel, 30, and is pivotally connected to the ram, 4, by pins 31, 31.

The pin, 21, on which the door engaging hook arm, 24^a, is carried passes through the door lifting arms, 32, 32, which are pivotally mounted on the ram head 4^a, by pin, 33, and are connected through link, 34, and bent lever, 35, which is pivotally connected to ram 4, to wheels, 36, which are arranged to travel on inclined tracks, 37, carried on the carriage.

Upon rods, 38, 38 which at their upper ends pass through brackets, 39, 39, attached 95 to the door lifting arms 32, and at their lower ends are connected by collars with pins, 40, are carried door unlatching hooks, 41, 41, which are arranged to engage with the door lock bars, 42, 42.

Upon the pin, 40, are carried door holding rollers, 43, 43, which are pushed against the lower portion of door, D, by the action of counter weight, 44, through link 45, and counter-weight lever 46, which is pivotally 105 connected to the ram head 4^a, by pin, 47.

The operation of the device is as follows:—The carriage 1, having been properly located in front of the door to be removed the ram, 4, is advanced by means of motor, 110

6, the rack, 9, being held from independent movement by the action of spring 23, on lever, 16, and rack, 9, and ram, 4, are moved forward until the thrust rollers, 22, impact 5 pinge against the door frame the shock of impact being absorbed by spring, 23.

The thrust rollers, 22, and thrust arms, 19, then hold pin, 18, stationary, so that further advancement of the rack, 9, causes 10 the lever, 16, to swing about the pin, 18, as a fulcrum, thus further compressing spring, 23, and retarding the forward movement of the ram, 4, to an extent determined by the inequality in the distance of the connecting 15 pin, 17, from the ends of the thrust lever, 16. Rack, 9, then moves forward in its guides, 10, taking with it ram 4 by reason of the spring, 23, and connecting pin, 17, and continues to do so until the door engaging hook, 24, enters socket, 26, in the door, D, as shown in Fig. 1 of the drawings, the shock of impact, being again absorbed by spring, 23. Too great a penetration of socket 26, by hook, 24, is prevented by contact of 25 cheeks, 25, with the outer surface of the door. Meanwhile the door holding rollers, 43, have impinged against the lower portion of the door, D, and thus arrested further forward movement of link, 45. The 30 forward movement of ram, 4, however, has pushed forward the fulcrum pin, 47, thus causing the counterweight, 44, to be lifted and to hold the rollers, 43, against the door with a pressure determined by the length of 35 the counterweight lever arm, 46, which may be varied to suit the requirements.

The parts are then in position for lifting the door engaging hook, 24, into engagement with the door socket, 26, and for lifting the 40 latch bars, 42, from engagement with the latch hooks, and the forward movement of ram, 4, and rack, 9, is stopped.

Hand wheel, 30, is then rotated causing, 45 arm, 24^a, to be moved about pin, 21, as a fulcrum, thus lifting hook, 24, and engaging it firmly with door socket, 26. At the same time through the action of arms, 49, which are connected to pin, 48, and the connected arms, 50, 51, which latter are engaged with rods, 38, rods 38 are lifted, thus causing the unlatching hooks, 41, to engage and lift from their sockets the lock bars, 42, so that the door, D, is ready to be removed from its frame. Further rotation 50 of wheel, 30, causes a downward pressure on pin, 21, thus taking up any lost motion in arms, 32, 34, and 35, and seating wheels, 36, firmly on their tracks. Motor, 6, is then set in operation so as to move pinion, 55 8, in a clockwise direction, thus retracting rack, 9, and causing arm, 16, to rotate on pin, 18, as a fulcrum thus pushing back the ram, 4, through the thrust of pin, 17, and pulling back the top of the door, D, 60 through the engagement of the lifting hook, 65

24, with its socket, 26, and tearing off the mud seal of the door from the top downward, the bottom of the door being held in place by the door holding rollers, 43, through the action of counterweight, 44. 70

At the same time the spring 23, has kept the thrust arms, 19, pushed forward thus holding the thrust rollers, 22, against the door frame with a force at least equal to that exerted in pulling back the upper portion 75 of the door so that no dislodgment of the door frame is possible. During this time the rack, 9, has moved backward with greater speed than the ram, 4, until lug, 12^a, has engaged with stop, 11^a, the shock 80 of impact being absorbed by spring, 13, after which the rack, 9, and ram, 4, move together, and the thrust rollers, 22, no longer engage the door frame.

The door is now removed from its socket 85 by the backward movement of the ram and, by reason of the inclination of the ram and also the movement of wheels, 36, in their inclined tracks, 37, is at the same time lifted vertically until the ram has reached the limit 90 of its backward movement. As the door begins to rise at the instant of the beginning of its backward movement it makes no contact with the door sill or oven platform as it moves. 95

In replacing the door the ram is moved forward as before until the bottom of the door, which is held advanced by the counterweight, 44, and rollers, 43, is in place in the 100 door frame. The top of the door is then pushed into place by door engaging hook, 24. The engagement, at this time, of the thrust rollers, 22, with the door frame causes, as before, rotation of arm, 16, about pin, 18, as a fulcrum and thereby automatically retards the speed of movement of the ram, carrying the engagement hook 24. By this means the gradual and slow fitting of the door into place is automatically effected. Opportunity is thus afforded the operator 110 for any required adjustment and a proper fit of the door into the door frame is secured. By the time the door has been thus fitted into place, lug, 12, has engaged with stop, 11. The full forward movement of 115 the rack, 9, is then transmitted to the ram and the door is thereby forced firmly into its position. The door engaging hook is then released from its socket and the latch bars, 42, are dropped into place by rotating 120 the wheel, 30, in the reverse direction.

A diagrammatic side view of a modification of the device is shown in Fig. 8 in which the device is suspended from overhead tracks for use on the discharge side 125 of the oven. In this modification, the track, 37, not only serves as a guide for the rollers, or wheels, 36, but also supports the wheels, 5, on which the ram, 4, travels. In place of the levers and link 32, 34, 35 are also sub- 130

stituted brackets, 35^a, which are mounted on the ram, 4, by pin, 52, and are directly attached to the rollers 36. The method of operation is the same as above described.

By my invention means are provided for 5 tilting the top of the door outward before removing it from its socket thus breaking the mudding with a tearing action from the top downward and thus with a much less expenditure of power than when the door 10 is moved directly outward, and the door frame is held in place with a force equal to that applied in breaking the door seal, so that no dislodgment of the frame is possible.

15 The door may also be lifted from its seat along any desired curve, according to the degree of inclination of the ram, 4, and the track, 37, and the lifting mechanism is engaged with the door and the door is returned 20 to its seat without shock or violent impact, the advantages of which will be readily apparent to those skilled in the art.

What I claim as new and desire to secure by Letters Patent is:—

25 1. In an oven door extractor the combination of a carriage, a reciprocating member mounted thereon, door engaging mechanism carried by said member, means for tilting the top of the door outward from the 30 door frame and means for applying pressure to the door frame equal to that applied in withdrawing the top of the door from the door frame.

2. In an oven door extractor the combination of a carriage, a reciprocating member mounted thereon, a rack carried by said member whereby reciprocating movement is imparted thereto and arranged to have 40 movement independent of said member and means actuated by the movement of said ram for first tilting outward the top of the door and then removing the door from its frame and means actuated by the movement 45 of said rack for holding the door frame in place during said tilting movement.

3. In an oven door extractor the combination of door engaging mechanism, means for tilting the top of the door outward from its frame and means for applying pressure to the door frame during such tilting movement.

4. In an oven door extractor the combination of a reciprocating member arranged 55 to move along an inclined path upwardly from the oven, door engaging means carried by said member and means whereby the door is first tilted outward from the top and then removed from its frame in its tilted 60 position and along an upward sloping path by the backward movement of said reciprocating member.

5. In an oven door extractor the combination of a reciprocating member arranged to 65 move along an inclined path upwardly from

the oven, door engaging means carried by said member, means whereby the door is first tilted outward from the top and then removed from the door frame in its tilted position and along an upward sloping path 70 by the backward movement of said reciprocating member and means carried by the reciprocating member for applying pressure to the door frame during said tilting movement. 75

6. In an oven door extractor the combination of a reciprocating member, door engaging means carried thereby and arranged to be moved forward into engagement with the door, arms connected with the reciprocating member and arranged to engage with and apply pressure to the door frame and means actuated by the engagement of said arms with the door frame to decrease the rate of forward movement of the door 80 engaging means. 85

7. In an oven door extractor the combination of a reciprocating member comprising a rack and a ram movable thereby and arranged to have movement independent thereof, door engaging means carried by the ram, a member connected with the rack and arranged to engage with and apply pressure to the door frame and means actuated by the engagement of said member 90 with the door frame to decrease the rate of movement of the ram relative to the rack. 95

8. In an oven door extractor the combination of a reciprocating member, door engaging means carried by said member, arms arranged to contact with the door frame while the door is being removed from and fitted into its frame and means actuated by contact of said arms with the door frame 100 to decrease the rate of forward movement 105 of the door engaging means.

9. In an oven door extractor the combination of door engaging means, means for moving said door engaging means forward 110 into engagement with the door, means for applying pressure to the door frame and means actuated by said pressure applying means for decreasing the rate of forward movement of the door engaging means before its engagement with the door. 115

10. In an oven door extractor the combination of means for breaking the seal of the door from the top downward, means for applying pressure to the door frame during the breaking of the seal, means for removing the door from its frame and returning it thereto and means actuated by said pressure applying means for reducing the rate of forward movement of the door 120 before it comes into re-engagement with its frame. 125

11. In an oven door extractor the combination of a motor, means actuated by the motor for withdrawing the door from and 130

returning it to place in its frame and means for retarding the speed at which the door is returned to its frame before it makes contact with the frame and independently of the speed of the motor.

12. In an oven door extractor the combination of a motor, means actuated by the motor for withdrawing the door from and returning it to place in its frame and means for automatically retarding the speed at which the door is returned to place in the door frame before it makes contact with the frame.

13. In an oven door extractor the combination of a motor, door engaging means, means actuated by the motor for bringing said door engaging means into position for engaging the door and means for retarding

the speed at which said door engaging means is brought into position for engaging the door before it makes engagement with the door and independently of the speed of the motor.

14. In an oven door extractor the combination of a motor, door engaging means, means actuated by the motor for advancing said door engaging means into position for engaging the door and means for automatically retarding the speed at which said door engaging means is advanced into position for engaging the door before it makes engagement with the door.

In testimony whereof I affix my signature, this 25th day of November, 1921.

JULIUS BECKER.
